UNITED STATES PATENT OFFICE.

WILLIAM D. FRAZER, OF DAIN, WEST VIRGINIA, ASSIGNOR OF ONE-FOURTH TO J. B. DODGE, OF RICHWOOD, WEST VIRGINIA.

HEATING-STOVE.

1,190,396.

Specification of Letters Patent.

Patented July 11, 1916.

Application filed November 1, 1915. Serial No. 59,132.

To all whom it may concern:

Be it known that I, WILLIAM D. FRAZER, a citizen of the United States, residing at Dain, in the county of Nicholas and State 5 of West Virginia, have invented certain new and useful Improvements in Heating-Stoves, of which the following is a specification, reference being had to the accompanying drawings.

10 This invention relates to heating apparatus, and more particularly to a stove or heater of such construction that a number of stoves may be connected together so that the products of combustion from one stove 15 will pass into the next succeeding stove and so on to the point of final discharge, each stove being adapted, however, to be used separately from the other stoves.

15 The primary object of the invention is to 20 construct a stove of the character described which may have a fire built in it and be used in the ordinary or usual manner, but that the products of combustion from a stove on the floor below may be passed 25 through it either directly or by a circuitous course.

20 A further object of the invention is to provide a stove of the construction described with an entirely rotatable grate, this grate 30 carrying a back wall which may be rotated either to the front of the fire space or chamber or to the rear thereof.

25 Still another object of the invention is to provide means whereby fresh air may be 35 taken into the ash pit beneath the grate and the products of combustion carried directly up out through a flue, whereby products of combustion from a stove below may be directed either beneath the grate of the first- 40 named stove and then directly out through the flue, or beneath the grate and by a circuitous course around a heating chamber and out through the flue, or whereby the products may be directed upward at the 45 back of the stove without passing through the grate thereof and so out through the flue.

50 Other objects of my invention are to improve on the detailed construction of stoves of this character whereby they may be cheaply made and readily installed.

55 My invention is illustrated in the accompanying drawings, wherein:

Figure 1 is a vertical longitudinal section of a stove constructed in accordance

with my invention; Fig. 2 is a vertical section on the line 2-2 of Fig. 1; Fig. 3 is a horizontal section on the line 3-3 of Fig. 1; Fig. 4 is a section on the line 4-4 of Fig. 1; Fig. 5 is a diagrammatic view showing 60 how my improved stoves are arranged in houses; Fig. 6 is a vertical sectional view on the same line as Fig. 2 but showing a water reservoir disposed within the heating chamber 27.

65 I will first describe one of my improved stoves as illustrated in Figs. 1 to 4. This stove consists of the body 2 which is preferably of sheet iron and preferably elliptical in plan. This body is formed with the top 70 3 and the bottom 4. The front of the body has the usual fire door 5, and disposed around the body just below the fire door is the main frame casting 6 which has preferably an upwardly extending flange 7 whereby it is riveted to the body 2 or otherwise attached thereto. This main frame casting, 75 as shown in Fig. 3, is cut away at its forward end to provide a grate opening 8 and at its rear end to provide a draft opening 9 and at its middle as at 10, there being a sheet metal plate 11 fitted over this opening 10 so as to lighten the weight of the casting as much as possible. The middle of the casting 80 is supported upon a transversely extending 85 arch wall 12 which is bolted or otherwise attached to the side of the body, the casting 6 having downwardly extending flanges 13 engaging over the upper edge of the arched wall and assisting it in holding it in place. 90 It will be noted that the casting 6 constitutes a septum dividing the upper portion of the stove from the lower portion. Rotatably mounted in the grate opening 8 is the grate 14 which may be of any suitable form but 95 which is preferably a rotatable grate formed upon its lower face with the annular rack 15. This rack is engaged by a gear wheel 16 carried upon a short shaft 17 which extends out at the front of the main casting and to which a crank is adapted to be applied. Detachably mounted upon this rotatable grate is the semi-cylindrical back wall 18 having in the form of half of a fire pot. Mounted in the opening 9 is a damper 19 which is pivotally supported in any suitable manner and is preferably mounted upon a pintle 20 which extends out through the side wall of the body so that the damper may be rotated either to an open or a closed position. 105 110

The bottom 4 of the stove is formed with an opening 21 and depending from the bottom of the stove around this opening is the flue section 22 which is adapted to be connected to a flue section extending from a stove on the lower floor. Disposed in this flue section 22 is a damper 23 whereby passage through this flue section may be controlled, this damper being mounted upon a pintle 24 which extends out to the front of the stove and is provided with a handle 25 whereby it may be manipulated and the damper closed or opened or otherwise regulated. Disposed in the top 3 of the stove and in vertical alinement with the flue section 22 is a flue section 26 which is adapted to be connected with a flue leading up to a stove on the floor above or to the chimney of the house.

Disposed within the body 2 and extending transversely across it is a heating chamber 27 which preferably opens at the sides of the stove and is provided with suitable doors. This heating chamber may be either used for cooking or for the heating of water. Thus it may be used either as an oven or as a water back, as desired. Extending downward from the top 3 to the top wall of the chamber 27 is a vertical wall or partition 28 formed with an opening 29, passage through which is controlled by a damper 30. It will be seen that the back wall 18 extends upward approximately to the top of the heating chamber 27 and that when the back wall 18 is in its rearward position it is spaced a relatively slight amount from the front wall of the heating chamber 27.

In Fig. 5 I show how a plurality of stoves, each disposed on one floor of the house, may be connected to each other so that the products of combustion from a lower stove will pass upward and through an upper stove. The several stoves are designated respectively 2^a, 2^b and 2^c. The flue connecting the several stoves is designated 31, and the final discharge flue is designated 32.

In practical use any one or more of the stoves may be fired. When the fire is built in any one of the stoves its fire pot wall 18 is turned to the rearward position and a damper 33 in the door of the ash pit below the grate 15 may be opened to permit the entrance of fresh air beneath the fire. If the fire is built in one of the upper stoves when there is no fire in the lower stove the damper 19 is closed. The air may be allowed to pass up through the flue section 22 and will then be deflected into the ash pit 30 and pass up through the grate. The damper 30 is of course opened so as to allow the products of combustion to pass from the fire space up the flue 26. If it is not desired to draw air from the stove below, the damper 22 is closed. The stove will then act in all

respects precisely like an ordinary stove. If a fire is built in a lower stove and there is no fire in any of the upper stoves and it is not desired that the products of combustion from the lower stove shall be used to heat the upper floors of the house, then the dampers 23 of the stoves are opened, the dampers 19 of the upper stoves are opened, and the dampers 30 of the upper stove are closed. Under these circumstances the products of combustion will pass directly up from the lower stoves through the rear portion of the upper stoves and out through the final discharge flue. If on the other hand it is desired to utilize the heat escaping from the lower stove in the upper stove the damper 12 of the upper stoves is closed and the products of combustion from the lower stoves are directed laterally into the ash pit or box beneath the grate, then up through the grate and then out through the flue 26 by way of the opening 27. If it is desired to utilize this heat for the purpose of heating the chamber 27 then the damper 30 in the upper stove is closed and the heat as a consequence will pass up over the back wall or fire pot wall 18 and down in front of the chamber 27, then along the bottom of the chamber and then up and out through the flue section 26. Thus the heat is caused to take a circuitous course and heat the contents of the chamber 27. It will of course be understood that heat from a lower stove may also be passed into an upper stove when there is a fire burning in the upper stove 100 and that this heat may be directed either up through the rear portion of the upper stove or up through the fire in the upper stove.

It will be obvious that by rotating the grate 14 the back wall 18 may be carried around toward the front of the stove, thus tending to prevent the radiation of heat from the front of the stove but providing for the passage of heat upward through the opening 9 and around on all sides of the heating chamber 27. When turned in the position shown in Fig. 1, however, this fire back permits the building of a fire upon the grates 14 and acts to radiate the heat outward and forward.

My improved stove construction provides means whereby heat which would be otherwise wasted may be conserved, and I have found in actual practice that under most circumstances enough heat will be secured from a lower stove or stoves to heat the upper floors of a house. Furthermore, it will be obvious that a stove may be so controlled as to apply this heat to the best advantage and that the stove may carry its own fire but heated by heat passing upward from a stove below or utilize both the heat of its own fire and the escaping heat of the stove below. The chamber 27 may be used for baking purposes or as a means of water 120 heating.

heating, it being obvious that a water heater may be inserted within this chamber and operatively connected to the pipes of the house. A water heater itself may be disposed in place of this chamber, in other words, a structure composed of water coils, and I regard this as entirely within the purpose of my invention. I have illustrated in dotted lines a series of water coils disposed in the space occupied by the chamber 27, and in Fig. 6 I have illustrated a water reservoir 34 which may be inserted into the heating chamber 27 or withdrawn therefrom so as to permit this heating chamber to be used for cooking purposes.

Another advantage in using a plurality of superposed stoves of the construction illustrated in Fig. 1 and connected up as shown in Fig. 5, is that the ashes accumulating in an upper stove may be readily forced back to the opening 21 and then allowed to drop down the flue 31 into the stove below and so eventually into the cellar or other collecting place for ashes into which the opening 21 of the lowermost stove will discharge. This may be readily accomplished with the stove illustrated in Fig. 1 by opening the dampers 23 and 20 of the lower stoves and opening the damper 23 of the uppermost stove and then pushing the ashes collected in the ash pit back under the supporting arch or bridge 12 to the opening 21. By this means there will be no necessity of collecting ashes from the stoves on the upper floors of a house, but all the ashes may be gathered from the stove on the lower floor or from an ash pit in the cellar.

Having thus described the invention, what is claimed is:

1. A stove of the character described having a fuel supporting grate, an outlet flue section in its bottom and an inlet flue section in the top rearward of the grate and in approximate alinement whereby products of combustion from another heating appliance may be passed upward through the rear of the stove, means for controllably admitting fresh air beneath the grate, a heating chamber disposed rearward of the grate, and means for directing all products of combustion entering through the inlet flue either directly upward through the stove rearward of the heating chamber, forward, beneath and through the grate and over the heating chamber and to the outlet flue, or upward through the grate, then downward and rearward beneath the heating chamber and then upward through the outlet flue.

2. A stove of the character described including a body having a septum extending horizontally across it adjacent its lower end, the septum having a grate supporting opening in its front and an opening in its rear, a grate supported in the first-named opening, a damper controlling the passage

through the second-named opening, an inlet flue in the bottom of the body beneath the last-named opening in the septum, a damper controlling the passage through the inlet flue, an outlet flue disposed in the top of the body and in approximate alinement with the inlet flue, a draft opening disposed in the body below the grate whereby fresh air may be admitted to the space beneath the grate, a deflecting obstruction disposed within the body, and a damper in the upper portion of the body above the deflecting obstruction which when closed causes the products of combustion from the space above the grate to pass downward around said deflecting obstruction.

3. A stove of the character described including a body, a septum extending horizontally across the body and adjacent its lower end and having a grate supporting opening in its forward end and an opening in its rear end, a grate supported upon the septum over the grate opening, a damper controlling the passage through the second-named opening, an inlet flue section in the bottom of the body below the second-named opening in the septum, a damper controlling passage through said inlet section, an outlet flue section disposed in the top of the body and in approximate alinement with the inlet flue section, and a back wall extending upward from the rear portion of the grate, and means for controllably admitting fresh air beneath the grate.

4. A stove of the character described including a body, a septum extending across the body and formed with a grate opening in its forward end and with an opening in its rear end, a grate rotatably mounted in the grate opening, a damper controlling the passage through the second-named opening, an inlet flue section in the bottom of the body beneath the second-named opening, a damper controlling the passage therethrough, an outlet flue section disposed in the top of the body approximately in alinement with the inlet flue section, a back wall mounted upon and extending upward from the grate, and means for rotating said grate to shift the back wall from a position intermediate of the ends of the stove to a position in the front of the stove.

5. A stove of the character described including a body, a septum extending horizontally across the lower portion of the body and formed with a grate opening and an opening in its rear end, a grate rotatably mounted in the grate opening, a damper controlling the passage in the second-named opening, an inlet flue section at the bottom of the body beneath the second-named opening in the septum, a damper controlling the passage through said inlet flue section, an outlet flue section in the top of the stove approximately in alinement

with the inlet flue section, a draft door in the body below the grate whereby fresh air may be admitted therethrough, means for rotating the grate, a rear wall semicylindrical in form and mounted upon the grate, a heating chamber disposed within the body above the septum and rearward of the grate, a partition extending from the top of the body down to said heating chamber and formed with an opening, and a damper controlling said opening.

6. In a heating stove, a rotatable grate and a fire pot wall carried upon the margin of and extending partly around the grate and rotatable therewith from a position in front of the stove to a position at the rear of the stove.

7. In a heating stove, a grate and a fire pot wall extending partly around and disposed above the margin of the grate, said fire pot wall being rotatably mounted for movement into a position adjacent the front

of the stove and in front of the grate or to a position at the rear of the stove and at the rear of the grate.

8. In a heating stove, a grate, a heating chamber disposed rearward of the grate and a fire pot wall extending partly around and disposed above the margin of the grate, said fire pot wall being rotatably mounted for movement into a position adjacent the front of the stove and in front of the grate whereby to reflect heat against said heating chamber and shield the front of the stove or to a position at the rear of the stove and at the rear of the grate whereby to shield the heating chamber and reflect heat toward the front of the stove.

In testimony whereof I hereunto affix my signature in the presence of two witnesses. 40
